UNITED STATES PATENT OFFICE.

EDWARD GRANT HARRIS, OF JEFFERSON BARRACKS, MISSOURI.

HAIR-CUTTING INSTRUMENT.

1,224,462.

Specification of Letters Patent.

Patented May 1, 1917.

Application filed July 24, 1916. Serial No. 111,012.

To all whom it may concern:

Be it known that I, EDWARD GRANT HARRIS, a citizen of the United States, residing at Jefferson Barracks, in the county of St. Louis, and State of Missouri, have invented certain new and useful Improvements in Hair-Cutting Instruments, of which the following is a specification.

This invention relates to instruments for 10 use in cutting and trimming hair and has as one of its objects to provide an instrument of this class which may be readily and quickly manipulated in a manner to evenly and effectually cut and trim the hair of the 15 head, cutting the hair to the length desired by the user of the instrument.

Another aim of the invention is to so construct the device that the same will be adapted to hold any ordinary safety razor 20 blade or the device may, if desired, be employed in connection with an ordinary razor by application to the blade thereof.

Another aim of the invention is to provide means whereby the blade may be adjusted with relation to the points of the 25 teeth of the device thereby adapting the device to cut hair to practically any desired length.

In the accompanying drawings:

30 Figure 1 is a perspective view of the device embodying the present invention, the same being supplied with an ordinary safety razor blade.

Fig. 2 is a top plan view of the device.

35 Fig. 3 is a perspective view of the blade holder removed from the body of the device.

Fig. 4 is a detail vertical longitudinal sectional view through one end of the device.

40 Fig. 5 is a vertical transverse sectional view through the mid-portion of the device.

Fig. 6 is a view in elevation of one of the 45 adjusting screws for the blade holder of the device.

The instrument embodying the present invention includes a body member which is 50 hollow and preferably formed from sheet metal and this body member comprises a back 1 and a plurality of teeth which are indicated by the numeral 2, the teeth extending 55 from the lower portion of the opposite sides of the hollow back 1 and the teeth in themselves being hollow or, in other words, each tooth comprises spaced portions 3 which gradually converge toward the lower 60 end of the tooth and are there integrally united as indicated by the numeral 4 in Fig.

4 of the drawings. The body is open at both ends so as to permit of the insertion and removal of the razor blade at either end of the said body and in order to provide for adjustment of the blade holder the back 1 of the body at the ends thereof is struck down to provide portions 5 located below the plane of the upper side of the back and each of these portions is formed with a threaded 65 opening 6 for a purpose to be presently pointed out. In striking down the upper side of the back at the ends thereof, openings 7 are provided through which may project portions of the blade holder with which 70 portions the adjusting screws to be herein-after described, coact.

The blade holder comprises a back 8 and downwardly converging resilient sides 9 between which the back of the razor blade is to 75 be inserted in the manner shown in Figs. 3 and 5 of the drawings, the said blade being indicated by the numeral 10. As before stated, the blade may be in the nature of a safety razor blade of any of the well known 80 forms, or it may be the blade of an ordinary razor, and while the sides 9 are here illustrated as constructed and arranged to engage and hold a blade having a relatively wide or wedge shaped back, nevertheless, it will be 85 understood that said sides 9 may be formed so as to frictionally grip and hold a thin safety razor blade, or a supplemental means as, for example, a pair of wedge strips may be employed in connection with the thin 90 razor blade and the said sides 9 of the holder. The back 8 of the holder is provided with terminal extensions 11 having portions 12 which extend upwardly at right angles from the extensions 11 and which at their upper 95 ends are provided with outwardly laterally extending ears 13 each having a notch 14 formed therein. In assembling the blade holder with the body of the device, the holder is arranged within the said body with the ears 100 13 projecting through the openings 7 at the ends of the back of the body in the manner clearly shown in Figs. 1 and 4 of the drawings. Adjustably threaded into each opening 6 is the shank 15 of an adjusting screw 105 16 which shank is provided at its upper end with a milled head 16 permitting of ready adjustment of the set screw, and below the head with a reduced portion or neck 17 defined by shoulders 18 at its upper and lower 110 ends, the neck 17 being rotatably received within the notch 14 of the respective ear 13

and the said shoulders coacting with the upper and under sides of the said ear so that when the screw is adjusted the corresponding end of the blade holder will be adjusted 5 to vary the position of the cutting edge of the blade with relation to the ends of the teeth 2, it being understood that in this manner the cutting edge may be located more or less closely to the said ends of the teeth 10 whereby to determine the length to which the hair will be cut as the device is moved over the head. Of course, when the device is held substantially perpendicular to the head the hair will be cut or trimmed less 15 closely than when the device is disposed and held more nearly flat against the head, the device being caused to assume this latter position, however, in trimming the hair around the neck. 20 Having thus described the invention, what is claimed as new is:

1. In a device of the class described, a body member having a hollow back and provided with teeth, the said back of the body member 25 being provided at each end with an opening and beyond each opening with a bearing portion spaced in stepped relation below the plane of the top of the back, a blade holder disposed within the body and having 30 a back and resilient portions designed to grip the blade to be held with the cutting edge of the blade located in juxtaposition to the said teeth, the said back of the blade holder being provided at each end with an 35 upward extension terminating in an outwardly extending ear projecting through

the opening in the respective end of the back of the body member and above the respective bearing portion, and adjusting screws coacting with the said ears and bearing portion. 40

2. In a device of the class described, a body member having a hollow back and provided with teeth including spaced portions converging toward their ends, the said back of 45 the body member being provided at each end with an opening and beyond each opening with a portion having a threaded aperture and spaced in stepped relation below the plane of the top of the back, a blade holder 50 disposed within the body and having a back and resilient side portions designed to grip the back of a blade to be held with the cutting edge of the blade extending between the spaced portions of the teeth, the 55 said back of the blade holder being provided at each end with an upward extension terminating in an outwardly extending ear projecting through the opening in the respective end of the back of the body member, each 60 ear having a notch formed therein, and adjusting screws threaded into the said apertures and having their shanks provided with circumscribing grooves receiving the walls of the notches in the said ears of the blade 65 holder, the ears projecting above the portions of the back of the body member in which the said threaded apertures are formed.

In testimony whereof I affix my signature. 70

EDWARD GRANT HARRIS. [L. s.]
